CLAIM

The ornamental design for a receiver for indicating the arrival of mail, as shown and described.

DESCRIPTION

FIG. 1 is a front, top and side perspective view of a receiver for indicating the arrival of mail embodying the design of the present invention;

FIG. 2 is a front elevational view thereof;

FIG. 3 is a rear elevational view thereof, with the wire broken away to indicate indeterminate length;

FIG. 4 is a side elevational view thereof, the side opposite being a mirror image of the side shown in FIG. 4; and,

FIG. 5 is a top plan view thereof, the side opposite being a mirror image of the side shown in FIG. 5.
